C. D. ROGERS.
Device for Pointing Wire.

No. 230,718.

Patented Aug. 3, 1880.

FIG. 1.

FIG. 2.

WITNESSES:

*Henry J. Farmer,
W. H. Thurston.*

INVENTOR:

Charles D. Rogers.

UNITED STATES PATENT OFFICE.

CHARLES D. ROGERS, OF PROVIDENCE, RHODE ISLAND, ASSIGNOR TO THE
AMERICAN SCREW COMPANY, OF SAME PLACE.

DEVICE FOR POINTING WIRE.

SPECIFICATION forming part of Letters Patent No. 230,718, dated August 3, 1880.

Application filed April 29, 1878.

To all whom it may concern:

Be it known that I, CHARLES D. ROGERS, of the city and county of Providence, and State of Rhode Island, have invented an Improved 5 Device for Pointing Wire Previous to the "Drawing" of the Same, the said device to be attached to a wire-drawing machine or used separately therefrom, as may be desired, the same being fully described in the following 10 specification and illustrated in the accompanying drawings, in which—

Figure 1 represents a top view or plan of my device attached to a wire-drawing machine, certain parts being cut away the better to 15 show construction; Fig. 2, an elevation of the same, and Fig. 3 a view of the face of one of the dies and the segmental gear to which it is attached.

The operation of wire-drawing by means of 20 a draw-plate and other proper mechanism—such, for instance, as that described in Letters Patent of the United States granted to me February 27, 1877—is too well known to need particular description. It will therefore only 25 be necessary, for an understanding of my device, that certain features of the operation be mentioned.

The wire, as is well known, is received from the rolling-mill in coils, and previous to being 30 drawn it is necessary to reduce the diameter of an end of said wire in order that it may be easily inserted into and passed a desirable distance through the draw-plate. This operation of reducing the diameter of the end is 35 also necessary in all the succeeding stages of reducing the wire to the requisite sizes. Likewise, when from any cause the wire breaks during the process of drawing, the undrawn end has to be reduced in diameter for the 40 purposes above specified.

Now, heretofore the operation of reducing an end of a coil of wire as it comes from the mill has been performed by more or less cumbersome machinery, which has been entirely 45 distinct and separate from the drawing-machine, and in the succeeding operations of drawing the reduction of the diameter of the ends has been performed entirely by hand with a common vise and file, necessitating considerable comparative expense, not only for the

time occupied by the workman in filing the required length of wire to the proper size, but by the stoppage of the machinery during such labor.

It has also long been a shop custom to diagonally clip with hand-shears for pointing the end of wire, and shears for such use have been heretofore applied to wire-drawing machines. The operations of filing and shearing result in more or less waste of wire, and the wire-point 55 afforded thereby is to that extent weakened and unfitted for withstanding the gripe and strain of the clamp by which the initial drawing is performed.

The object of my invention is to furnish a 60 simple and effective device which may be attached to and worked by and in connection with a wire-drawing machine, its location with relation to the same being such as not to interfere with the proper working of said machine, and at the same time to be convenient 65 of access to the workman. Also, to so arrange certain of its parts that the end of any usual size of wire being worked may be compressed, and thereby properly and desirably reduced 70 in diameter by one and the same device, as will hereinafter appear. An end of wire reduced in diameter by compression is much 75 stronger than one reduced by the removal of metal, and much less waste is incurred.

Having described the objects of my invention, I will now proceed to a description of its construction, it being understood that the device is attached to the wire-drawing machine, although it may be used entirely distinct and 80 separate therefrom, as will also hereinafter appear.

A represents a table or bench, to which the device is secured. B is the "coiling-drum" of the wire-drawing machine, supplied with the 85 clamp b, and C is the vertical shaft which gives revolution to the drum, the parts B, b, and C being arranged in the manner described in the Letters Patent abovementioned, granted February 27, 1877.

D is a cam attached to the shaft C, to which a continual rotary motion is given, the said cam operating upon an arm, E, having upon its end, if desired, an anti-friction roller, the 90 said arm being attached to or forming a part 95 100

of a segmental gear, F, pivoted to the casing G at f, and being held in contact with the cam D by the force of a spring, d, (shown in dotted lines in Figs. 1 and 2,) which is attached 5 to a pin upon said arm or upon the gear F. Working in and in engagement with the segmental gear F is a fellow, F', the counterpart of the former, with the exception of the arm E, the said gear F' being pivoted to the casing 10 G at f'.

Attached to and above the gears F F' are plates H H', which carry a pair of segmental-faced dies, K K', the said dies having studs upon their backs and being secured to the 15 plates H H' by nuts or in any preferable manner.

The faces of the dies K K' are scored with any desirable number of slightly-tapering half-round grooves, as k k', &c., Fig. 3, the 20 mouths of said grooves being enlarged for the purpose of allowing the wire to be passed easily through. These tapering grooves k k', &c., are of varying sizes, corresponding with the different sizes of wire to be drawn, so that 25 no matter what size of wire within certain limits is being worked suitable grooves in the dies will be found to properly reduce the diameter of the end of said wire. Furthermore, when soft wire is being worked—that 30 is, wire that will bear in one drawing a reduction of two sizes—it is only necessary to twice introduce into the device the wire to be reduced, and it will be properly fashioned to pass through the draw-plate the requisite 35 distance to be seized by the clamp or griper, whose office is to draw through a sufficient amount to reach and be attached to the coiling-drum, the said operation being well known.

In order to properly "line" the wire and 40 guide the same to the proper pair of reducing-grooves, the casing G is furnished with a guide-plate, L, Fig. 2, having a series of apertures, l l', &c., graded in diameter to accommodate the different gages of wire, the 45 face of the plate being, if desired, stamped opposite to the orifice of each aperture with the number of the wire the said aperture is intended to receive. The rear side of the casing G is also furnished with a stop-plate, 50 (not shown in the drawing,) whose office is to govern the length of wire inserted.

Before describing the actual and full operation of my device it will perhaps be necessary to state that the shaft C of the wire-drawing machine is in continual revolution, 5 regardless of whether or not the coiling-drum is clutched to it. It will therefore be seen that, the cam D being attached to said shaft, motion will be constantly communicated to 10 the dies unless some arrangement be made for temporarily disconnecting the said cam from the shaft or of preventing its action upon the arm E. An arrangement for this purpose may be so applied that the insertion of the 5 wire will operate to connect the cam D to the

shaft or bring the arm E into contact with said cam to actuate the dies, the use of such an arrangement being immaterial to the operation of the device.

Having described the construction of my device and explained its connection with certain parts of a wire-drawing machine, I will proceed to its operation, which is that technically known as "back-rolling."

It being desired to reduce the diameter of 75 the end of a coil of wire, a time is selected when the dies are at the farthest point of the path of their inward motion, the wire is inserted into and passed through the proper aperture in the guide-plate L, the length so inserted being governed by a stop-plate attached to the casing. The cam D being in revolution actuates, through the arm E and segmental gears H H', the dies K K', which close upon the wire, reducing its diameter, and at the 80 same time carrying it outward toward the attendant and freeing it from the device. The operation of reducing the diameter is thus simply and quickly completed, and the workman can now proceed to the drawing by passing the said wire through the draw-plate, pulling through a sufficient amount, attaching the same to the coiling-drum by means of the clamp b, clutching the said drum to the shaft, and the operation of drawing will go forward. 85

Although in the operation of my device I have described it as attached to a wire-drawing machine, yet it can be used entirely distinct from said machine, it being only necessary to supply the device with a revolving shaft to 90 which to attach the cam D.

It is to be understood that I do not limit myself to the precise construction hereinbefore described and shown, as the same may be varied—as, for instance, the segmental gears 105 may each be furnished with a lever-arm and operated upon by a double-acting cam, and the said gears may be so fashioned as to carry the dies, and the plates H H' be dispensed with.

I am well aware that my pointing-dies operate on the well-known principle of back-rolling, and that back-rolling rolls have been heretofore provided with guides and a stop-plate; but, so far as my knowledge extends, segmental gear-dies actuated by a cam and lever, as herein shown, were never used for that purpose prior to my present invention.

What I claim, and desire to secure by Letters Patent, is—

The combination, with the driving mechanism of a wire-drawing machine, of the segmental dies grooved for pointing wire and geared together, the operating-cam, the lever, the guide-plate, and the stop-plate, substantially as described.

CHARLES D. ROGERS.
